UNITED STATES PATENT OFFICE.

JAMES HARTMAN, OF BERN, KANSAS.

BUTT-BOARD FOR GRAIN-BINDERS.

1,169,031.

Specification of Letters Patent. Patented Jan. 18, 1916.

Application filed April 26, 1915. Serial No. 23,900.

To all whom it may concern:

Be it known that I, JAMES HARTMAN, a citizen of the United States, residing at Bern, in the county of Nemaha and State of Kansas, have invented new and useful Improvements in Butt-Boards for Grain-Binders, of which the following is a specification.

This invention relates to butt boards or devices for evening the butts of grain in grain binding harvesters.

The invention has for its object to produce a construction under which a butt board which is supported for orbital movement in a plane parallel to that of the binder deck over which the grain is passing is provided with a movable apron or tail piece which is effective in lining up the grain with a great degree of precision.

20 A further object of the invention is to simplify and improve the construction of the frame whereby the butt board is supported for orbital movement.

25 A further object of the invention is to provide the said carrying frame with a shield also engaging the butt ends of the grain and serving as a guide for the movable apron.

With these and other ends in view which 30 will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood 40 that no limitation is necessarily made to the precise structural details therein exhibited, but that changes, alterations and modifications within the scope of the claims may be resorted to when desired.

45 In the drawings,—Figure 1 is a front view of a portion of the elevator casing and binder deck of a grain binder equipped with the invention. Fig. 2 is a sectional view taken on the line 2—2 in Fig. 1. Fig. 50 3 is a sectional view taken on the line 3—3 in Fig. 2. Fig. 4 is a plan view of the binder deck showing the invention applied and adjusted in a somewhat different position than in Fig. 2. Fig. 5 is a sectional view taken on the line 5—5 in Fig. 4.

Corresponding parts in the several figures are denoted by like characters of reference.

15 designates a portion of the elevator casing and 16 the binder deck of an ordinary self-binding grain harvester. 60

The elevator casing is provided with bearings 17 supporting a rock shaft 18 having an arm or bracket 19 which extends above the binder deck in spaced and substantially parallel relation thereto, said arm 65 or bracket supporting a substantially rectangular frame B comprising inner and outer end members 20, 21 and top and bottom members 22, 23, the latter being extended beyond the end member 21 to support an angular shield 24 having a flange 25 provided with a vertical slot 26.

The butt board 27 is provided at one end with a bracket 28 which is pivoted on a crank 29 on a shaft 30 which is journaled in 75 suitable bearings on the elevator casing and which receives rotary motion from some moving part of the machine through the medium of a wheel or sprocket 31 with which it is provided. The other end of the 80 butt board is connected by a link 32 with one arm 33 of a bell crank C which is fulcrumed on the inner end member 20 of the frame B, the other arm 34 of said bell crank being connected by a link 35 with a wrist 85 pin 36 associated with the crank 29. Rotary movement of the shaft 30 will thus, through the medium of the crank 29 and the bell crank C and related parts, produce an orbital movement of the butt board in a plane 90 substantially parallel to the plane of the binder deck. The butt board 27 is provided at its tail end with an apron or tail piece 37 which is pivotally connected therewith and which is guided through the slot 26 in 95 the flange portion of the angular shield 24. The latter, being relatively stationary, it follows that when the butt board is in motion, the apron 37 will slide to and fro through the slot 26 and will receive a rocking or vibratory movement whereby it will be caused to impinge on the butt ends of the stalks of grain when moving in the direction thereof.

This operation is auxiliary to the butt board proper, the engaging face of which is 100 formed or provided with ratchets 38 for the purpose of effectively engaging the grain butts.

To provide for operation of varying lengths of grain, the frame B which is 110

swingly supported by the bracket 19 of the rock shaft 18 may be adjusted by means of an adjusting rod 39, one end of which is pivotally connected at 40 with said frame, 5 while the other end is adapted to be adjustably connected with a stationary part of the machine in a customary and well known manner.

It will be seen from the foregoing description, taken in connection with the drawings, that grain passing from the elevator over the binder deck will be first engaged by the face of the butt board proper and next by the tail piece or apron 37. Passing beyond the range of said apron the butt ends of the grain will be engaged by the relatively stationary shield 24, whereby any irregularities will be corrected, and the grain will be delivered to the packers in an even and perfect manner.

Having thus described the invention, what is claimed as new, is:—

1. A frame, a bell crank fulcrumed on one end member of said frame, a shaft supported for rotation and having a crank provided with a wrist pin, a butt board having a bracket pivoted on the crank, a link connecting the wrist pin with one arm of the bell crank, a link connecting the butt board with the other arm of the bell crank, and means for rotating the shaft having the crank, thereby imparting an orbital movement to the butt board.

2. A swingingly supported frame, a bell crank fulcrumed on one end member of said frame, a shaft supported for rotation and having a crank provided with a wrist pin, a butt board having a bracket pivoted on the

crank, a link connecting the wrist pin with one arm of the bell crank, a link connecting the butt board with the other arm of the bell crank, and means for rotating the shaft having the crank, thereby imparting an orbital movement to the butt board; in combination with means for securing the swingingly supported frame at various adjustments.

3. A butt board supported for orbital movement, a swingingly supported frame with which the butt board is connected, a shield carried by the frame and having a slot, a tail piece connected pivotally with the butt board and guided through the slot of the shield, means for adjusting the swingingly supported frame and for securing it at various adjustments, and means for actuating the butt board.

4. In a grain binding harvester, a swingingly supported frame, a butt board supported for orbital movement, a link connection between the butt board and the swingingly supported frame, means for effecting adjustment of said frame and for securing it at various adjustments, a slotted shield carried by the swingingly supported frame and relatively stationary with respect to the butt board, and a tail piece pivotally connected with the butt board and guided by the slotted shield.

In testimony whereof I affix my signature in presence of two witnesses.

JAMES HARTMAN.
